NECKTIE HOLDER

Filed June 13, 1928

WITNESS:

Robert Lushy

BY *Victor J. Evans*

ATTORNEY

UNITED STATES PATENT OFFICE.

THOMAS J. DOWD, OF BRONX, NEW YORK.

NECKTIE HOLDER.

Application filed June 13, 1928. Serial No. 285,086.

This invention relates to improvements in necktie holders.

The primary object of the invention resides in a necktie holder for detachable engagement with the front collar button of the neckband of a shirt to press against the neck encircling portion of a tie to hold the knotted portion of the tie in proper position with respect to the front of a collar.

Another object of the invention is to provide a necktie holder by which the knot of a necktie may be held up against accidental drooping when in a tied condition upon a collar and against lateral shifting and which is substantially concealed behind the knot.

A further object is the provision of a necktie holder which may be quickly applied to the head of a collar button after the collar has been fastened, by snapping the same thereon.

A still further object is to provide a necktie holder which is simple in construction, inexpensive of manufacture, and neat and attractive in appearance.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a detail perspective view of my improved necktie holder in position upon the collar button of a shirt.

Figure 2 is an enlarged vertical sectional view on the line 2—2 of Figure 1.

Figure 3 is a front elevation of the holder per se.

Figure 4 is a front elevation of a modified form.

Figure 5 is an end elevation thereof.

Figure 6 is a front elevation of another modified form.

Figure 7 is a side elevation of the form of holder shown in Figure 6.

Figure 8 is a front elevation of a further modification.

Figure 9 is an end view of the holder shown in Figure 8.

Referring to the drawing by reference characters, and particularly to Figures 1 to 3 inclusive, the numeral 10 designates the preferred form of my invention which includes a metal head 11 having a socket 12 therein, the entrance to which is restricted by

a yieldable element 13. The head 11 may be termed the female element for receiving the rounded head 14 of a collar button 15. The exterior annular side wall of the head is provided with a circumferential groove 16 for receiving the eye 17 of a V-shape wire frame 18. The frame 18 is constructed of resilient wire and has its outwardly curved arms 19 curved backwardly as shown in Figure 3 of the drawing. The extreme and free ends of the arms terminate in loops or eyes 20 which are adapted to press against the neck encircling portion 21 of a four-in-hand tie 22 to hold the knot 23 thereof in proper position in the spaced front of a collar 24. The knot of the tie and outer folds of the collar conceal the holder from view. A link 25 maintains the eye 17 in clamped position upon the head 11.

In applying the holder to the collar button 15, the neckband and collar are fastened thereto in the usual way and the tie knotted and drawn and the head 11 pressed upon the head or male element 14. The holder may be readily removed by pulling upon the head 11 to free the same from engagement with the head of the collar button.

In Figures 4 and 5 of the drawing, I have shown a slightly modified form in which the eye 17 is soldered to the head 11 instead of being held clamped thereto by the link 25.

In Figures 6 and 7, I have shown a further modification wherein the holder is constructed of a single piece of resilient wire 90 bent midway between its ends into a hump or eye 26 having a restricted entrance opening, while the free ends are bent upwardly and backwardly to provide resilient arms 27 terminating in looped portions or eyes 28. In this form, the hump 26 is applied to the shank of the collar button just behind the head thereof.

Figures 8 and 9 show a further modification which is substantially the same in construction as the form shown in Figures 6 and 7 but instead of forming the holder of resilient wire, I stamp the same from a blank of flat resilient metal to provide an attaching eye 26' and resilient arms 27'.

In all the various forms of my invention, I employ an attaching means for applying the holder to the front collar button of a shirt, and provide outwardly diverging resilient arms for gently pressing upon the neck encircling portion of a knotted tie to support the knot in proper position at the front of the

collar. The article will be found easy to apply and remove and will serve to impart a neat appearance to the tie of a wearer.

While I have shown and described what I deem to be the most embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A necktie holder comprising a single piece of resilient material bent midway between its ends to provide an eye, outwardly curved arms extending from said eye and con-

stituting the free ends of the single piece of resilient material, and a link passing about said arms for restraining outward flexing thereof to maintain the size of said eye.

2. A necktie holder comprising a head having a socket therein for receiving the head of a collar button, a groove provided in the exterior of said head, a single piece of resilient material bent midway between its ends to provide an eye which is seated in said groove, the free ends of said material being curved in opposite directions to provide resilient arms.

In testimony whereof I have affixed my signature.

THOMAS J. DOWD.
